TREATMENT OF HYDROCARBONS

Kenneth M. Brown, Hinsdale, Ill., assignor to
 Universal Oil Products Company, Chicago, Ill.,
 a corporation of Delaware

Application December 24, 1948, Serial No. 67,203

11 Claims. (Cl. 196—32)

1

This invention relates to the treatment of hydrocarbons and more particularly to a combination of mutually related and interdependent steps comprising desulfurization of hydrocarbons and mercaptan decomposition of a selected fraction therefrom.

A particularly effective desulfurization process in commercial use at the present time is the Unisol process in which acidic organic compounds and particularly mercaptans are removed from gasoline by treatment with a caustic-methanol solution. In this process, a mercaptan fraction is separated from the other products, and in the present practice the mercaptan fraction is burned as fuel or otherwise disposed of. However, the mercaptan fraction contains valuable hydrocarbons, not only the hydrocarbons in solution in the mercaptans but also the hydrocarbon content of the mercaptan molecule and the present invention is directed to a novel method of recovering these hydrocarbons.

In a broad embodiment, the present invention relates to a combination process which comprises treating sour hydrocarbon oil with an alkali-solvent solution, separating a mercaptan fraction from said treating, subjecting said mercaptan fraction to decomposition to form hydrogen sulfide and hydrocarbon, and recovering said hydrocarbon.

In a specific embodiment the present invention relates to a combination process which comprises intimately contacting gasoline with caustic-methanol solution, separating treated gasoline from the caustic-methanol solution, regenerating said solution to separate an overhead fraction comprising mercaptans and methanol, separating a mercaptan fraction from a methanol fraction, subjecting said mercaptan fraction to high temperature treatment to form hydrogen sulfide and hydrocarbon, removing the hydrogen sulfide, and subjecting said hydrocarbon to contact with caustic-methanol solution.

While any suitable alkali reagent, including sodium hydroxide, potassium hydroxide, etc. and any suitable organic solvent which is more soluble in an aqueous solution of an alkali reagent than are hydrocarbons, including methanol, ethanol, propanol, acetone, ethylene glycol, glycol ethers, etc. may be used, the preferred treating reagent comprises an aqueous solution of sodium hydroxide or potassium hydroxide and methanol.

According to the present process, gasoline or fractions thereof containing acidic organic compounds are treated with the alkali-solvent solution at a temperature above the freezing point

2

of the solution. The preferred treating temperature is generally within the range of from about 80° to about 110° F., although in some cases lower or higher temperature may be used but the temperature usually will not be below about 25° and not above about 200° F. The pressure employed is usually within the range of from about 25 to about 200 pounds, although lower or higher pressures may be used in some cases.

10 As heretofore set forth, preferred treating reagent comprises an aqueous solution of sodium hydroxide and methanol. The quantity of sodium hydroxide solution may range from about 0.5% to 10% or more by volume based on the hydrocarbons to be treated, while the sodium hydroxide may be between about 35° and 50° Baumé and preferably between about 45° and about 50° Baumé. The methanol employed may be anhydrous or it may contain varying amounts 15 of water. However, as the water content of the methanol fraction increases, the concentration of the sodium hydroxide solution should be increased accordingly.

20 In accordance with the invention, gasoline containing mercaptans and usually phenols is contacted with the caustic-methanol solution under the conditions hereinbefore set forth. Sodium mercaptides and phenolates are formed and are dissolved in the caustic-methanol solution. This 25 solution is then separated from the hydrocarbons, the caustic-methanol being regenerated to convert the mercaptides into sodium hydroxide and mercaptans. The mercaptans, methanol and water are separated from the caustic and the latter is 30 returned for further use within the process. The 35 mercaptans are separated from a water-alcohol mixture, usually by settling under carefully controlled conditions which avoid turbulence. The 40 mercaptan fraction thus separated will contain varying amounts of hydrocarbons entrained 45 therein. Further, the mercaptan itself comprises a chemical combination of hydrocarbons and sulfur. In accordance with the present invention this mercaptan fraction is subjected to treatment to decompose the mercaptans into hydrogen sulfide and hydrocarbons. In a preferred embodiment of the invention the hydrocarbons are recycled within the system to be recovered along with the gasoline products of the 50 process, thereby resulting in an increased yield of desired gasoline.

55 The mercaptan decomposition step of the present invention may constitute any suitable process in which the mercaptan fraction, alone or in combination with other fractions, is sub-

jected to conversion at a temperature sufficient to decompose the mercaptans to hydrogen sulfide and to thereby liberate hydrocarbons. Usually most refineries will employ some form of high temperature conversion and, in accordance with a preferred embodiment of the invention, the mercaptan fraction is supplied to the existing high temperature process for conversion therein. As typical examples of suitable high temperature processes for use in accordance with the present invention, the following are mentioned.

(1) Catalytic cracking process, which may be of the fixed bed or moving catalyst types including the fluidized process, the moving catalyst process, the slurry type process, etc., wherein the charge is intimately contacted with the catalyst at a temperature of above about 750° F. Particularly suitable cracking catalysts comprise compositions of silica-alumina, silica-magnesia, silica-zirconia, silica-alumina-magnesia, silica-alumina-zirconia, etc.

(2) Catalytic reforming process in which the charge is contacted with a catalyst fostering dehydrogenation and aromatization as well as desulfurization reactions at a temperature above about 800° F. Similarly, this process may be either of the fixed bed or of the moving catalyst type. Particularly suitable catalysts for reforming processes include alumina-molybdena, alumina-chromia, etc., and the reforming may be effected in the presence or absence of hydrogen.

(3) High temperature catalytic desulfurization process in which the charge is contacted with a suitable catalyst fostering conversion of mercaptans to hydrogen sulfide at a temperature above about 500° F. but below about 800° and preferably below about 750° F. This process may be effected in the presence or absence of hydrogen and usually will employ catalysts comprising alumina, bauxite, clay, nickel, nickel sulfide, molybdenum sulfide, etc.

(4) Thermal cracking process in which the charge is converted in the absence of a catalyst at a temperature above 800° F. and a pressure above 50 pounds per square inch, and generally at a temperature of 900° to 1050° F. and a pressure of 200 to 500 pounds.

(5) Thermal reforming process in which the charge is converted in the absence of a catalyst at a temperature usually within the range of about 950° to about 1100° F. and at a pressure of from 100 to 1000 pounds.

Decomposition of mercaptans into hydrogen sulfide and hydrocarbons also may be effected in the presence of hydrogen and hydrogenation catalysts, such as, those containing molybdenum, molybdenum sulfide, nickel, nickel sulfide, etc. at temperatures below 500° F. and this method of mercaptan decomposition is also comprised within the scope of the present invention. Mercaptans decompose into hydrogen sulfide and hydrocarbons at less severe conditions than are required for the cracking or splitting of carbon to carbon bonds of hydrocarbons. Thus the decomposition of mercaptans may be effected at lower temperatures.

The invention is further illustrated in the accompanying diagrammatic flow drawing and the following description thereof. In the interest of simplicity the following description will be limited to the treatment of gasoline by means of a caustic-methanol solution, although it is understood that other sour hydrocarbon fractions including burner or heater oils, fuel oil, lubricating oil, etc. and other suitable alkali reagents and organic sol-

vents may be employed but not necessarily with equivalent results. Likewise, auxiliary equipment, such as valves, pumps, etc., have been omitted from the drawing in the interest of simplicity.

5 Referring to the drawing, the gasoline charging stock to the process, which may comprise straight run gasoline, thermally cracked gasoline, catalytically cracked gasoline or any gasoline or other hydrocarbon fractions containing acidic organic compounds and particularly mercaptans, is introduced to the process through line 1. When the gasoline charge contains hydrogen sulfide, the gasoline is directed into pre-wash zone 2, wherein the gasoline is intimately contacted with caustic solution introduced to zone 2 through line 3, whereby the hydrogen sulfide is converted into sodium sulfide and is retained in the caustic solution. In view of the fact that the caustic solution containing sodium sulfide cannot be regenerated by economical means, the caustic solution is preferably of low caustic concentration and generally will have a Baumé gravity of from about 5° to about 15°. The spent caustic is withdrawn from zone 2 through line 4, while the gasoline substantially free from hydrogen sulfide is withdrawn from zone 2 through line 5 and is directed through line 6 to mercaptan extraction zone 7. When the gasoline charged to the process does not contain hydrogen sulfide, it may be directed through lines 1, 8, 9 and 6 direct to extraction zone 7.

Extraction zone 7 may comprise one or a plurality of suitable extraction zones, preferably containing a suitable packing material. The packing material should not be detrimentally affected by the caustic, methanol and hydrocarbons at the operating conditions prevailing in this zone. A particularly suitable packing comprises carbon Raschig rings. Sodium hydroxide is introduced into the process through line 10 and is directed through line 11 into the upper portion of zone 7, preferably through a spray arrangement as indicated at 12. Usually sufficient sodium hydroxide is recycled within the process, in the manner to be hereinafter set forth, and the sodium hydroxide introduced through line 10 from an extraneous source will comprise the makeup reagent to replace that lost or withdrawn from the process. Methanol is introduced to the process through line 13 and is directed through line 14 at an intermediate point in zone 7. Here again the methanol will comprise primarily that recycled within the process, in the manner to be hereinafter set forth, and the methanol introduced through line 13 will comprise the makeup reagent to replace that lost or withdrawn from the process. Although, in the case here illustrated, the caustic and methanol are introduced at different points to zone 7, it is understood that in some cases the caustic and methanol may be commingled prior to introduction into zone 7.

In zone 7, the gasoline passes upwardly in intimate contact with the caustic-methanol solution, and the acidic organic compounds, such as mercaptans and phenols contained in the gasoline are converted into sodium mercaptides and phenolates. The rate of flow of the gasoline, caustic and methanol are so adjusted that the treated gasoline being withdrawn from the upper portion of zone 7 through line 15 contains substantially less mercaptans than the gasoline introduced through line 6. The treated gasoline may, if desired, be washed with water or otherwise treated to remove methanol or traces of alkaline reagent which may be entrained therein.

The mercaptides and phenolates formed in zone 7 are dissolved in the caustic-methanol solution, and the caustic-methanol solution is withdrawn from the lower portion of zone 7 through line 16 and is directed through heat exchanger 17 and line 18 into stripping zone 19. Zone 19 preferably contains a suitable packing material such as carbon Raschig rings and/or contacting means such as bubble trays, side to side pans, etc. In zone 19 the caustic-methanol solution is subjected to regeneration by heating, which in the case here illustrated comprises reboiling of the solution in the lower portion of the stripping zone. It is understood that other suitable means of supplying heat to the lower portion of this zone, such as by means of superheated steam, etc. may be employed. The temperature maintained in the lower portion of the stripping zone is substantially the boiling point of the caustic solution, which, with a 48° Baumé sodium hydroxide solution, will be of the order of 285° F. The temperature at the top of the stripping zone may be of the order of 200° to 250° F. depending in part on the temperature of the spent treating solution introduced thereto through line 18.

As a result of the heating, the sodium mercaptides are decomposed to mercaptans, with the liberation of an equivalent amount of sodium hydroxide. The sodium hydroxide is withdrawn from the lower portion of zone 19 through line 20, a portion thereof being recycled by way of line 21 into and through reboiler 22 and line 23 back to zone 19. Any suitable heating medium may be utilized in reboiler 22 in order to furnish the heat required for regeneration of the caustic-methanol solution. While all or a portion of the regenerated caustic solution may be withdrawn from the process through the extension of line 21 as illustrated, preferably all or a portion of the caustic solution is directed through line 24, heat exchanger 25 and lines 26 and 11 to zone 7 for further use in the process. The mercaptans, methanol and water are vaporized in zone 19 and are directed therefrom through line 27, condenser 28 and line 29 into separator 30. The condensate is permitted to settle and stratify in separator 30, whereby there a mercaptan layer and a methanol-water layer are formed. In order to assist in this separation, additional water may be introduced by way of line 31 into 27. This water may conveniently comprise a portion of the water being withdrawn from the bottom of the methanol column in the manner to be hereinafter set forth.

The mercaptan fraction separated in zone 30 will contain varying amounts of entrained hydrocarbons, depending upon the particular gasoline charging stock and the specific operating conditions employed in the process. The entrained hydrocarbons may range from 2% in an extreme case to as high as 50% or more of the mercaptan fraction. In addition, as hereinbefore set forth, the mercaptans comprise a chemical composition of hydrocarbons and sulfur. In accordance with the present invention, the mercaptan fraction is withdrawn from zone 30 through line 32 and is subjected to a mercaptan decomposition treatment, in a manner to be hereinbefore set forth, in order to recover both chemically combined hydrocarbon portion of the mercaptan molecule and the hydrocarbon in physical admixture with the mercaptan.

The methanol-water fraction is withdrawn from separator 30 through line 33 and is directed into methanol column 34. In zone 34 the aque-

ous methanol fraction is subjected to heating and distillation by any suitable means. Heating may be accomplished by use of a reboiler arrangement as illustrated or by the introduction of superheated steam into the lower portion of zone 34, etc. In zone 34, the methanol is separated from the water, and the latter is removed from the lower portion thereof through line 35. A portion of the water is recycled through line 36, reboiler 37 and line 38 back to zone 34, while the remaining portion is withdrawn through the extension of line 35 as illustrated. When desired, a portion of this water may be supplied through line 31 into line 27 as hereinbefore set forth or the water may be used to wash the treated gasoline being withdrawn through line 15, and the wash water may be returned to either caustic stripping zone 19 or methanol column 34. Methanol is removed from the upper portion of zone 34 through line 39 and is directed through condenser 40 and line 41 into receiver 42. The methanol is removed from receiver 42 through line 43, a portion thereof is recycled by way of line 44 to the upper portion of zone 34 to act as a cooling and refluxing medium therein, while the remaining portion may be removed from the process through the extension of line 43 as illustrated, but preferably is recycled at least in part through line 45 and 14 to mercaptan extraction zone 7 for further use therein.

In accordance with the present invention the mercaptan fraction withdrawn from separator 30 through line 32 is subjected to a mercaptan decomposition treatment and, as hereinabove set forth, this treatment may take one of several forms. In one embodiment of the invention the mercaptan fraction comprises the sole charging stock to a high temperature treatment step and this accomplished by directing the mercaptan fraction through lines 32 and 46 into and through heater 47, wherein the mercaptan fraction is heated to a temperature required to effect decomposition of the mercaptans into hydrogen sulfide and hydrocarbons. The heated products are then directed through line 48 and line 49 and through reactor 50, which may or may not contain a catalyst, and then are directed through line 51 to fractionator 52. In some cases, zone 50 may be omitted and the desired heating and reaction time obtained in the coils of heater 47, in which case the heated products are directed through lines 48 and 51 to fractionator 52.

In another embodiment of the invention the high temperature heating step may comprise a conventional catalytic or non-catalytic cracking, reforming or high temperature desulfurization process. Cracking and reforming operations are effected at a temperature of from about 800° F. to about 1000° F. High temperature desulfurization is effected at a temperature of above 500° F. and generally of from about 650° to about 800° F. In this embodiment of the invention the crude oil, topped crude, gas oil, gasoline or other charge to the high temperature step of the process is introduced through line 53 and is directed, along with the mercaptan fraction being supplied by way of line 32, and 46 through heater 47 and the subsequent zones of the process. When hydrogen is to be employed, particularly in the case of reforming or high or low temperature desulfurization, it may be introduced to the process through line 54 or in any other suitable manner.

The separation to be effected in fractionator 52 will depend upon the particular type of process employed. When this process comprises a crack-

ing operation, components boiling higher than gasoline are separated from gasoline and lighter boiling components. The higher boiling components are withdrawn from the lower portion of zone 52 through line 55, a portion thereof being recycled by way of line 56, reboiler 57 and line 58 to zone 52, while the remaining portion may be withdrawn from the process through the extension of line 55 or may be recycled by way of lines 59 and 46 for further conversion within the process. In this case, the overhead fraction withdrawn from fractionator 52 will comprise gasoline and lighter components and are directed through line 60, condenser 61 and line 62 to receiver 63. Normally gaseous components including hydrogen sulfide are removed from the process through line 64, while the gasoline is withdrawn from receiver 63 through line 65, a portion thereof being recycled by way of line 66 to the upper portion of zone 52 to serve as a cooling and refluxing medium therein. The gasoline being withdrawn through line 65 will contain mercaptans formed during the high temperature conversion of the heavy charging stock introduced through line 53, and, in accordance with the present invention, is directed through line 67 for treatment in the caustic-methanol step of the process. Usually, the gasoline fraction will contain some hydrogen sulfide and preferably the gasoline fraction is directed through lines 67 and 1 to prewash zone 2. However, in some cases prewash zone 2 may be omitted and the gasoline fraction may be directed through lines 67, 9 and 6 to mercaptan extraction zone 7.

When desired, the gasoline fraction withdrawn through line 65 may be directed through line 68 to stabilizer 69, wherefrom normally gaseous components including hydrogen sulfide are removed from the upper portion through line 70 and are directed through condenser 71 and line 72 to receiver 73. The uncondensed gases are withdrawn from the process through line 74, while the condensate is withdrawn from receiver 73 through line 75, a portion being recycled by way of line 76 to the upper portion of zone 69 to serve as a cooling and refluxing medium therein, while the remaining portion is withdrawn from the process through line 77. The gasoline separated in stabilizer 69 is withdrawn from the lower portion thereof through line 78, a portion thereof being recycled by way of line 79, reboiler 80 and line 81 to zone 69, and the remaining portion is withdrawn from the process through line 79 but preferably is supplied through lines 67 and 1 or lines 67 and 9 for further treatment within the process in the manner hereinbefore set forth. In general, the stabilized gasoline will contain less hydrogen sulfide than the gasoline withdrawn from receiver 63 and, therefore, when the gasoline is free from hydrogen sulfide or the hydrogen sulfide content is sufficiently low, prewash zone 2 may be omitted.

When the charge to the high temperature step of the process comprises a gasoline and the mercaptan fraction from separator 30, separation in fractionator 52 will depend upon whether any material boiling above the range of gasoline is formed during the high temperature treating step. When such high boiling material is formed, the fractionator will function as hereinbefore described. On the other hand, when no high boiling components are present in the products supplied to zone 52, fractionation therein will be effected to separate normally gaseous components from gasoline boiling components, the former be-

ing withdrawn through line 60 from the upper portion of zone 52 and the gasoline components being withdrawn through line 55 from the lower portion. In this case, the gasoline may be directed through lines 55 and 82 to line 67, to be supplied either through lines 1 or 9 for further treatment within the process.

In another embodiment of the invention, the gasoline from the high temperature step of the process is supplied to the caustic-methanol treatment and the mercaptan fraction from separator 30 is supplied to the high temperature treatment. In this way the mercaptans are recycled to extinction; that is, the sulfur containing compounds are removed from the process only in the form of hydrogen sulfide, with the exception of the small amount of sulfur compounds which may be entrained in the other products of the process.

In certain cases mercaptans of the mixture from zone 30 may resist decomposition in the high temperature treatment and would eventually accumulate within the process. To meet this contingency, line 83 is provided to withdraw stable mercaptans from the process. This is readily accomplished by withdrawing a bleed stream either continuously or periodically by way of line 83.

It will thus be seen that the present invention provides for the recovery of hydrocarbons from the mercaptan fraction, which thereby improves the yields of desired hydrocarbons recovered from the process.

The following examples are introduced to illustrate further the novelty and utility of the present invention but not with the intention of unduly limiting the same.

Example I

A thermally cracked gasoline containing about 0.06% mercaptan sulfur is subjected to mercaptan extraction in the presence of an aqueous solution of 48° Baumé caustic and methanol. The extraction zone is maintained at a temperature of about 100° F. and a pressure of 75 pounds per square inch. The spent caustic-methanol solution is heated to a temperature of about 210° F. by indirect heat exchange and is regenerated in the caustic stripping column, employing a temperature of about 285° F. in the lower portion of the stripping column. The mercaptan fraction withdrawn from separator 30 is supplied to a catalytic cracking process to which a gas oil charge is being supplied. The catalytic cracking is effected in the presence of a silica-alumina catalyst at a temperature of about 900° F. Hydrogen sulfide is separated from the catalytically cracked gasoline which also contains the hydrocarbon components recovered from the mercaptans.

In another operation, thermally cracked gasoline is treated in the caustic-methanol process as hereinbefore set forth and the mercaptan fraction withdrawn from separator 30 will contain approximately 75% mercaptans and 25% hydrocarbons. The mercaptan fraction is supplied to a conventional thermal cracking process to which topped crude is charged. The thermal cracking is effected in the absence of a catalyst at a temperature of about 950° F. In the thermal cracking process, 60% of the mercaptans from receiver 30 are converted into hydrogen sulfide and hydrocarbons. The thermally cracked gasoline, containing hydrocarbons liberated from the mercaptan fraction, as well as 40% unconverted mercaptans from receiver 30 and additional mercaptans

formed in the cracking step, is recovered as a product from the thermal cracking step and is recycled to the caustic-methanol step, wherein the mercaptans are separated from the gasoline and are recovered in the mercaptan separator. The mercaptans are continuously recycled to the thermal cracking step and in this manner are substantially completely converted into hydrogen sulfide and hydrocarbons.

I claim as my invention:

1. A combination process which comprises treating sour hydrocarbon oil with a caustic-solvent solution, separating from the treating step a mercaptan fraction, simultaneously subjecting a second hydrocarbon oil to a high temperature conversion treatment, supplying said mercaptan fraction to said high temperature treatment to form hydrogen sulfide and hydrocarbon therefrom, and supplying mercaptan-containing hydrocarbons from the high temperature treatment to the first mentioned treating step.

2. The process of claim 1 further characterized in that said high temperature treatment comprises conversion of oil heavier than gasoline at a temperature of from about 800° to about 1000° F.

3. The process of claim 2 further characterized in that said high temperature treatment is effected in the presence of a cracking catalyst.

4. A combination process which comprises subjecting thermally cracked gasoline containing mercaptans to treatment with a caustic-methanol solution, recovering a mercaptan fraction from the products of the caustic-methanol treatment, commingling said mercaptan fraction with an oil heavier than gasoline and subjecting the mixture to conversion at a temperature of from about 800° to about 1000° F., in order to convert at least a portion of the mercaptans into hydrogen sulfide and hydrocarbons and to convert the oil heavier than gasoline into gasoline components, separating a gasoline fraction containing mercaptans from the products of the last mentioned conversion, and supplying said gasoline fraction to treatment with caustic-methanol solution as aforesaid.

5. A combination process which comprises treating gasoline with a caustic-methanol solution, separating from said treating a mercaptan fraction, subjecting said mercaptan fraction in admixture with an oil heavier than gasoline to conversion in the presence of catalyst under conditions to convert at least a portion of the mercaptans into hydrogen sulfide and hydrocarbons and to produce gasoline from said heavier oil, separating hydrogen sulfide and a gasoline fraction from the resultant products, and recycling said gasoline fraction to treatment with caustic-methanol solution as aforesaid.

6. The process of claim 5 further characterized in that the recycle of mercaptans within the process is continued until substantially all the mercaptans are converted into other compounds.

7. A combination process in which cracked gasoline is subjected to treatment with caustic-methanol solution to remove mercaptans, sepa-

rating a mercaptan fraction from said treating, commingling said mercaptan fraction with straight run gasoline and subjecting the mixture to high temperature treatment in the presence of a catalyst to convert mercaptans to hydrogen sulfide, separating a gasoline fraction and subjecting the same to treatment with caustic-methanol as aforesaid.

8. A combination process which comprises 10 treating gasoline with a caustic-methanol solution, separating from said treating a mercaptan fraction, subjecting said mercaptan fraction in admixture with another hydrocarbon oil to conversion in the presence of hydrogen and a hydrogenation catalyst under conditions to convert 15 at least a portion of the mercaptans into hydrogen sulfide and hydrocarbons, separating hydrogen sulfide and a gasoline fraction from the resultant products, and recycling said gasoline fraction to treatment with caustic-methanol solution as aforesaid

9. A combination process which comprises 20 treating sour hydrocarbon oil with an alkali-solvent solution, separating from the treating step a mercaptan fraction, simultaneously subjecting a second hydrocarbon oil to a high temperature conversion treatment, supplying said mercaptan fraction to said high temperature treatment to form hydrogen sulfide and hydrocarbon therefrom, and supplying mercaptan-containing hydrocarbons from the high temperature treatment to the first mentioned treating step.

10. A combination process which comprises 25 treating sour hydrocarbon oil with an alkali solution, separating from the treating step a mercaptan fraction, simultaneously subjecting a second hydrocarbon oil to a high temperature conversion treatment, supplying said mercaptan fraction to said high temperature treatment to form hydrogen sulfide and hydrocarbon therefrom, and supplying mercaptan-containing hydrocarbons from the high temperature treatment to the first mentioned treating step.

11. A combination process which comprises 30 treating sour hydrocarbon oil with a caustic solution, separating from the treating step a mercaptan fraction, simultaneously subjecting a second hydrocarbon oil to a high temperature conversion treatment, supplying said mercaptan fraction to said high temperature treatment to form hydrogen sulfide and hydrocarbon therefrom, and supplying mercaptan-containing hydrocarbons from the high temperature treatment to the first mentioned treating step.
